(57) **CLAIM**

The ornamental design for a mMIMO device chassis as shown and described.

DESCRIPTION

FIG. 1 is a front, left, top isometric perspective view of a mMIMO device chassis showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a front, right, top perspective view thereof;

FIG. 9 is a front, left, bottom, isometric perspective view thereof;

FIG. 10 is a front, right, bottom, isometric perspective view thereof;

FIG. 11 is a rear, right, top, isometric perspective view thereof;

FIG. 12 is a rear, left, top, isometric perspective view thereof;

FIG. 13 is a rear, right, bottom, isometric perspective view thereof;

FIG. 14 is a rear, left, bottom, isometric perspective view thereof;

FIG. 15 is a front, left, top isometric perspective view of an alternate embodiment of a mMIMO device chassis showing my new design;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top view thereof;

FIG. 21 is a bottom view thereof;

FIG. 22 is a front, right, top perspective view thereof;

FIG. 23 is a front, left, bottom, isometric perspective view thereof;

FIG. 24 is a front, right, bottom, isometric perspective view thereof;

FIG. 25 is a rear, right, top, isometric perspective view thereof;

FIG. 26 is a rear, left, top, isometric perspective view thereof;

FIG. 27 is a rear, right, bottom, isometric perspective view thereof; and,

FIG. 28 is a rear, left, bottom, isometric perspective view thereof.

(Continued)

The dotted lines represent portions of the mMIMO device chassis that form no part of the claimed design.
